ACTUATING MEANS

Elmer E. Harper, Monrovia, Calif.; Esther Pardee Harper, executrix of said Elmer E. Harper, deceased

Application February 9, 1944, Serial No. 521,597

1 Claim. (Cl. 74—105)

1

The present invention pertains to valves and valve mechanism, and the primary purpose of the invention is to provide an improved type of packless valve construction together with appropriate operating connections adapted to function as hereinafter described.

Accordingly one of the principal objects in view is to devise a construction in which valve stem packing is eliminated by the use of a combination of tube and rod elements so arranged as to develop a torque action in effecting the operating or control function as required. This result may be accomplished by a combination of the tube and rod elements arranged one inside the other, whereby the rod element operates as a direct medium for transmission of the control action while the outer tube (by being connected with the rod at one end but independently fixed or anchored at its other end) opposes the rotation of the rod, thereby introducing its torque action as a factor in the operation, in an effective manner.

In carrying out the invention, it is a further object to provide a construction of the character indicated in which the operating or control function may be transmitted in either direction, depending upon the type of duty to which it is to be applied. The construction is further adapted for either manual or automatic control or regulation.

It is also an object of my invention to provide a simplified and yet strong and sturdy construction of relatively few parts adapted to be assembled together and operated in a foolproof manner. To this end the construction is comprised of operating connections adapted to withstand very heavy external pressures while sacrificing no advantages as to accuracy and sensitiveness of operation.

The improvements are intended to be especially useful in connection with operations involving the handling of corrosive substances, such as in the feeding of chlorine materials and the like, though in no wise limited to such operations.

With the foregoing general object in view, as well as minor objects as will hereinafter appear, the invention will now be more specifically described by reference to the accompanying drawing, illustrating a practical form of apparatus which has been found satisfactory for the embodiment of my proposed improvements, after which those features and combinations deemed to be both novel and patentable will be particularly set forth and claimed.

In the drawing—

Figure 1 is a top plan view showing a packless valve unit embodying the present improvements—certain portions of the housing structure being broken away to disclose parts on the interior;

Figure 2 is a vertical longitudinal sectional

view, representing a section taken on the line 2—2 of Figure 1;

Figure 3 is a transverse sectional view, being a section taken on the line 3—3 of Figure 2; and Figure 4 is an elevation showing one end of the unit.

Referring now to the drawing in detail, the improved construction is illustrated as comprising a valve body or housing 10 forming an interior 10 valve compartment or chamber 12, at one end of which is provided an outlet or discharge fitting 14, and adjacent to the same end of the compartment is also provided a suitable inlet fitting 16, illustrated as held in place by screws 18—see Figure 1.

The inlet fitting 16 is formed with a sleeve 20 projecting inside the chamber or compartment 12 and terminating in a valve seat 22 for a needle valve 24 which is mounted axially in a valve spool 26 and held in place therein by means of a somewhat loose connection with a pin 27; and, as shown, the axial bore of the spool 26 is slightly oversize for the valve element 24 to permit limited lateral play of the needle valve for valve-seating purposes.

One end of the valve spool 26 is slotted and engages slidably with the end of the sleeve 20, while the opposite end of said spool is reduced and mounted slidably in a vertical slot 28 in the side wall of the housing 10; and above and below this end of the spool a pair of adjusting screws 29 may be employed for maintaining the spool in horizontal alignment with the sleeve 20, and moreover the horizontal depth of the slot 28 is sufficient to permit the longitudinal sliding movement of the spool as required for the opening and closing action of the valve (see Figure 3).

The valve spool 26 is provided with one or more annular slots or grooves 30—the drawing illustrating two of such slots or grooves, which are spaced a suitable distance apart for separate engagement with key lugs or fingers 32 formed on blocks or brackets 34 which are drilled to fit over the ends of a pair of torque tubes 36. Each of the torque tubes 36 is equipped with a rod or shaft 38 having free fitting relation within the tube and secured thereto as well as to the corresponding block or bracket 34 by a common pin 40. As illustrated in Figure 3, the inner end of each tube 36 is plugged with a sealing material 42 and removably journaled in an opening 43 in the end wall of the housing 10, and its opposite end is securely and permanently anchored as well as sealed within an opening 44 in a removable end plate 46 forming the opposite end wall of the chamber or compartment 12 and held in place by suitable screws 47.

The rods or shafts 38 project out and beyond the outer ends of the tubes 36, and are secured to a crank assembly 48 which is provided with

split clamping lugs 50 and screws 51 for that purpose, as illustrated in Figure 4. The top portion of the crank assembly includes a bar or link pivotally connected with the crank arms as shown in Figures 1 and 4 and having an opening 52 for removable engagement with one end of a pivoted operating lever 54 for which a fulcrum pin 56 is provided on the upper face of the housing 10, said lever extending longitudinally over the housing and having its opposite end engaged by a coil spring element 58 which tends normally to transmit a valve-closing movement to said lever; and for counteracting said spring action the opposite side of the lever is engaged by the tip of an operating or adjusting screw 60 threaded through an upright bracket element 62. A keeper member 64 extending loosely through an opening 65 in the lever 54 and through the coil spring 58 is anchored at its opposite ends in the bracket element 62 and another bracket element 66 on the top of the housing member 10—see Figures 1 and 4.

A top inspection opening 68 is provided over the sliding valve spool 26, and a removable cover plate 70 is secured over said opening by means of suitable screws 72, as illustrated in Figures 1 and 2.

It will be understood that by means of the foregoing construction the movements of the lever 54 will be transmitted through the crank assembly 48 to the tube and rod elements 36 and 38, in which a torque or twisting action is produced, with the result that some rotation of the key or lug elements 32 is likewise produced, thereby effecting a sliding longitudinal movement of the valve spool and its needle valve 24. The arrangement described is that which is adapted to produce opening movement of the valve as the lever 54 is moved against the pressure of the spring 58; and since said spring tends to seat the valve in closed position it is apparent that by adjusting the screw 60 in counteraction to said spring the valve can be operated either into closed position or set and maintained in open or any given partly open position, as may be required. In addition to being manually controlled in this manner, it is also apparent that the valve may be operated entirely automatically by completely retracting (or dispensing with) the screw and attaching a conventional control connection, such as indicated at 75 in Figure 1, to the operating lever 54 at a suitable point, for operating the valve in conjunction with other control mechanism, as is often required in plants employing chemical feeding devices (as in water purification plants) for which the present improvements are particularly well adapted.

It is obvious that a packless valve structure of this type affords decided advantages over certain prior packless valve constructions, such as those of the diaphragm type, as illustrated in my Patent No. 2,293,647, dated August 18, 1942. The present improved device is not only simpler but stronger construction, and is adapted to operate under much heavier external pressures by virtue of the combination torque tube and internal rod or shaft insuring against any collapse of such transmitting elements while at the same time maintaining a high degree of sensitiveness in the control function.

Moreover the improved method of operation provides a substantially frictionless transmission of the operative action to the valve member; this

is a decided advantage over ordinary valve constructions using packing around the valve stem which develops friction with highly variable effects and in many cases preventing free response of the valve to the external actuating means. For this reason the entire absence of such packing in the improved construction renders the same especially suitable for automatic and proportional control applications.

The example of construction illustrated in the drawing shows a plurality of torque tube and shaft combinations in parallel, but it is to be understood that a single tube and rod or shaft assembly may be employed, if desired, when the operating conditions are not severe, or too great stresses are not imposed. The combination of a plurality of such assemblies in any required number provides a flexible means of meeting any operating conditions in a most practical manner.

Incidentally it may be pointed out that as regards the transmitting function of the torque action, it is immaterial in which direction the transmitting action is taking place, and that the direction may be reversed under some conditions, as where the exterior parts might be employed in connection with indicating means actuated from within the housing chamber to denote movements of a float or the like inside said chamber.

The materials employed in the foregoing construction will be such as are appropriate for the conditions to be encountered, and where corrosive substances are to be handled the construction will be of such a character as to withstand the corrosive action of such materials. Accordingly, the torque tube may be of hard silver under some conditions, or simply of plastic material under other conditions; the rod or shaft may be of bronze, or silver-plated steel construction, and the other interior parts may be of suitable materials having non-corrosive properties where necessary. The casing or housing 10 may be of cast brass, or of plastic construction, or a cast iron jacket may be used having a lining of an appropriate material.

From the foregoing, therefore, it will be clear that I have devised a practical and highly efficient construction for carrying out the stated purposes of my invention, and that the described embodiment of the improvements may of course be varied to adapt the same to meet varying conditions and requirements of operation; accordingly I desire to be understood as expressly reserving the right to make whatever changes or modifications may properly be deemed to fall within the spirit and scope of my invention as defined in the appended claim.

Having described my invention, what I claim and desire to secure by Letters-Patent is:

Actuating means of the character described comprising, a movable element, an operating member, and torque transmission means comprising a plurality of torque assemblies in parallel relation and each comprising a torque tube and shaft rod enclosed thereby and connected at corresponding ends and also operatively engaged with said movable element for jointly actuating the same, the other ends of the tube and rod of each of said assemblies being respectively anchored in fixed position and connected with said operating member.

ELMER E. HARPER.
